PILOT CASING FOR A LOCOMOTIVE

William C. Meyer and David R. Ohlwiler, Altoona, Pa., assignors to The Pennsylvania Railroad Company, Philadelphia, Pa., a corporation of Pennsylvania

Application July 17, 1936, Serial No. 91,153

5 Claims. (Cl. 105—2)

Our invention relates generally to pilots for railway vehicles and more specifically to coupler doors in pilot casings.

In the development of railway vehicles, streamlining has become an important factor calling for the removal of surface obstructions generally. The desirability of smoothing out the surface of the pilot is, however, not due to streamline requirements alone. It is now well recognized that there is great danger that objects coming into contact with a pilot will catch thereon and be carried along on the pilot unless the pilot is provided with smooth deflecting surfaces. It is thus obvious that the advantage of smoothness in and about a locomotive pilot is a most desirable end in view of both streamlining and the actual operation of the pilot.

The front coupler of a locomotive presents a difficult obstacle in the way of maintaining the continuity of the pilot surface. Inventors have tried to overcome this obstacle by housing the coupler in the pilot in such a way that the outer surface of the housed coupler conforms to the surface contour of the pilot around the coupling. With this in mind the general object of our invention may be stated as the smoothing out of the surface of pilots, particularly in the region of the pilot coupler.

Our invention in accomplishing this object departs from the other means heretofore considered for this purpose, in that a pilot casing is provided outside the pilot and coupler and this is made possible by a specially devised door in the region of the coupler. It is clear that if a pilot casing is adopted, some door is necessary and further that such a door must in its closed position be very close to the coupler. If the pilot casing and door are not placed close to the pilot, there will not be sufficient operating clearance between the vehicle coupled. Thus the more specific objects of our invention are concerned with a coupler door in a pilot casing.

Such a door must lock securely into the surrounding pilot casing; it must close easily and provide an unbroken surface; it must be close to the coupler and pilot beam when the door is closed; it must open easily and be housed securely in the open position; and it must be simple in structure and operation. These are the more specific objects of our invention which is generally directed to the smoothing out of the surface of the pilot of a railway vehicle.

Still other advantages will become apparent from the following detailed description of one

embodiment of our invention, reference being had to the accompanying drawings.

Fig. I is a side view of the front portion of a locomotive equipped with a streamline casing extending over the pilot as a pilot casing.

Fig. II is a front view of the same.

Fig. III is a partial end view taken as indicated by the lines III—III of Fig. I and showing the coupler door in the pilot casing.

Fig. IV is a vertical sectional view taken about the lines IV—IV of Figs. II, III and V, showing in dotted lines the coupler door in the open position.

Fig. V is a horizontal sectional view taken about the lines V—V of Figs. II and IV.

Fig. VI is a vertical sectional view taken about the lines VI—VI of Fig. V, showing the coupler door partly open with the roller engaging its guide.

Fig. VII is a fragmentary view of a portion 20 of the coupler door in its open position resting against an angle iron which constitutes a stop means.

Fig. VIII is a fragmentary sectional view taken about the lines VIII—VIII of Fig. III showing 25 how the guides in which the door operates join into the framing around the door opening in the pilot casing.

Fig. IX is a sectional view taken about the lines IX—IX of Fig. IV showing the way in 30 which the door rollers are mounted on the coupler door and how the rollers operate in the roller guides.

For the purposes of a detailed description, our invention will be regarded generally as comprising a coupler door 1, door rollers 2, roller guides 3 and fulcrum points 4, all set in a background composed of a pilot casing 5, and a pilot 6, including a pilot beam 7. In the interest of clarity the pilot coupler is not shown but it occupies its 40 usual place in the central part of the pilot and is pertinent only as background. The uncoupling mechanism, identified comprehensively by the numeral 10, is also background; it is described in detail in an application for United States 45 Letters Patent filed July 17, 1936 by Herman G. Larson under Serial No. 91,158.

The coupler door 1 is spaced closely to the coupler and the whole casing 5 is likewise close to the pilot 6. This provides a sturdy backing 50 to the casing 5 in case of severe collisions. The door 1 comprises a frame 11 composed of angle irons to which a strong sheet metal face 12 is secured. The face 12 is formed to fit into the general surface contour of the streamlining of 55

the pilot casing 5. The opening in the pilot casing 5 into which the door 1 fits is framed by top strip 13, bottom angle iron 15 and side angle irons 14, 16. The side angle irons 14, 16 are in two pieces with the upper pieces offset outwardly to the side to provide fulcrum points 4 on the upper ends of the two lower pieces 14. The fulcrum points 4 are the upper ends of the lower pieces of the side angle irons 14 and 16 and these fulcrum points 4 extend under the side edges of the door 1. Since the upper pieces of side angle irons 14 and 16 are offset to allow the door 1 to pass therebetween, the door 1 as it is swung back or forward will pivot on points 4 as fulcrum points. It should be noted that the face 12 extends beyond the door frame 11 and that the casing 5 around the door opening is recessed a corresponding amount. However, the upper ends of the side angle irons 14 are offset sufficiently 20 to allow the top of the door 1 to swing inwardly through the door opening, about the fulcrum points 4.

Bolted to the upper parts of the sides of the door frame 11 are roller carriers 19 on which 25 are mounted the rollers 2. These rollers 2 fit onto the guides 3 as the door 1 swings open about the fulcrum points 4. These guides 3 are mounted over the pilot 6 and curve upwardly at the middle in order to facilitate the operation of the door 1. The top part of the door 1 should be raised as the door 1 is moved inwardly because of the necessity of clearing the fulcrum points 4. Then as the door 1 approaches the horizontal, 30 it becomes desirable to have the top part lowered again. This is all taken care of by the curvature of the guides 3. These guides 3 are secured at their front ends to the lower pieces of the side angle irons 14 near the fulcrum points 4. Because the rollers 2 project laterally beyond the edges of the door opening, the door 1 35 cannot accidentally fall out of the door opening during operation.

When the door 1 is shut, it is locked in place at its bottom edge by two ordinary locking devices 25 operable by handles 26 which fold down 40 when not in use into circular recesses in the face 12 of the door 1. These handles are a convenient means for lifting the door 1 in opening and closing it. The door 1 is further locked in place by bolts 27 near the upper corners of and 45 behind the door 1. These bolts 27 extend through registered holes in the frame 11 and the side angle irons 14. Hinged access doors 28 in the pilot casing 5 provide access to these bolts 27 behind the casing 5, as well as access to the 50 handles of the uncoupling apparatus 10. The door 1 is retained in its open position by the stop means 30 which take the form of two upwardly 55 projecting metal pieces attached to the top of the pilot 5, see Fig. VII. The bottom edge of the door 1 simply abuts against the stop means 30 until lifted up and over them as the door 1 is pulled forward in closing.

The operation of the above described invention is as follows: To open the door 1, the bolts 60 27 are first unbolted by means of the access doors 28. The handles 26 are then grasped and the lower edge of the door 1 is pulled outwardly and upwardly. This results in rotating the door 1 about the fulcrum points 4 until the rollers 2

engage the guides 3. The top of the door 1 is now clear of the casing 5 and the door 1 is then pushed to the rear, the curvature in the guides 3 aiding in getting around the fulcrum points 4. As the guides 3 curve down at their rear ends 5 the door 1 will tend to come to rest in its open position. By positioning the bottom edge of the door 1 behind the stop means 30, the door 1 is securely retained in the open position. To close the door the above operation is simply reversed. 10 Thus our invention is simple in construction and operation. It provides a smooth surface for the pilot. The advantages of having the casing close to the pilot proper are directly due to the way in which the door is designed to operate. 15 This closeness not only provides clearance in coupling but also provides a strong backing for the pilot casing to withstand the more severe collisions.

Having thus described our invention, we claim: 20

1. In a front end construction for a railway vehicle a pilot beam, a pilot casing in advance thereof and supported thereon, a coupler door in said casing, a roller attached to the upper portion of said door, a guide extending rearwardly 25 from adjacent the side of said door and over said pilot beam to receive said roller, and a fulcrum point attached to said casing below said roller for contacting the inside of said door when said door is being operated in opening and closing. 30

2. The invention of claim 1 characterized further by a stop means for holding said door in the open position, said stop means providing an abutment to receive the bottom and forward edge of the door in its open position. 35

3. The invention of claim 1 characterized further by a locking means disposed behind the casing adjacent the side edge of said door for locking the door shut, and an access door in said pilot casing near said locking means for 40 access to said locking means.

4. The invention of claim 1 characterized by a locking means for locking the door shut at its top and bottom portions, said locking means firmly locking said door to said pilot casing. 45

5. In combination with a pilot of a railway vehicle having a pilot casing and a coupler mounted on said pilot, a coupler door in said casing spaced closely to said coupler to allow a working clearance for said coupler when said coupler door is in the raised position, a roller attached to the upper part of each side edge of the door, said rollers extending behind said door and laterally beyond the side edges thereof to a point behind the pilot casing proper, a guide for each of said rollers attached to the pilot and extending rearwardly from said door, fulcrum points positioned on the casing and adapted to engage the inner side of said door at points near the edges thereof and below said rollers during the operation of the door in opening and closing, each said guides being upwardly curved at the middle thereof with the end nearest the door in proximity to one of said fulcrum points, a stop means for holding said door in its open position, and a locking means for holding said door in its closed position. 50 55 60 65
